UNITED STATES PATENT OFFICE

137,462

DESIGN FOR AN EMBLEMATIC BADGE OR SIMILAR ARTICLE

Frank Manners, New York, N. Y.

Application October 13, 1943, Serial No. 111,343

Term of patent 3½ years

To all whom it may concern:

Be it known that I, Frank Manners, a citizen of the United States of America, residing at New York city, county of New York, and State of New York, have invented a new, original, and ornamental Design for an Emblemsatic Badge or Similar Article, of which the following is a specification, reference being had to the accompanying drawing, forming a part thereof wherein:

Figure 1 is a face view of an emblematic badge or similar article, showing my new design, and

I claim:

The ornamental design for an emblematic badge or similar article, as shown.

FRANK MANNERS.
